US0D1070800S

(12) **United States Design Patent** (10) Patent No.: **US D1,070,800 S**
(45) Date of Patent: ** Apr. 15, 2025

(54) **VIDEO BAR**

- (71) Applicant: **GN Audio A/S**, Ballerup (DK)
- (72) Inventors: **Iain Scott Pottie**, Måløv (DK); **Jacob Emil Ingemann Jensen**, Copenhagen (DK); **Thomas Richard Needham**, Ryslinge (DK)
- (73) Assignee: **GN Audio A/S** (DK)
- (**) Term: **15 Years**
- (21) Appl. No.: **29/870,516**
- (22) Filed: **Jan. 27, 2023**
- (51) LOC (15) Cl. **14-03**
- (52) U.S. Cl. **D14/125**; D14/144
- (58) Field of Classification Search
USPC D14/125, 239, 225, 149, 336, 144;
D16/202, 200, 208
CPC H04N 7/15; H04N 7/152; H04N 7/155;

(74) Attorney, Agent, or Firm — Vani Moodley, Esq.

(57) **CLAIM**

The ornamental design for a video bar, as shown and described.

DESCRIPTION

FIG. 1 is a first perspective view of a video bar, showing our new design.

FIG. 2 is a second perspective view of the video bar.

FIG. 3 is a zoom view of FIG. 1.

FIG. 4 is a zoom view of FIG. 2.

FIG. 5 is a front view of the video bar.

FIG. 6 is a rear view of the video bar.

FIG. 7 is a left view of the video bar.

FIG. 8 is a right view of the video bar.

FIG. 9 is a top view of the video bar.

FIG. 10 is a bottom view of the video bar; and,

FIG. 11 is a zoom view of FIG. 9.

Any broken lines in the drawings depict portions of the video bar that form no part of the claimed design.

1 Claim, 10 Drawing Sheets
